(57) **CLAIM**

The ornamental design for a refrigerator, as shown and described.

DESCRIPTION

FIG. 1 is a top, front and right side perspective view of a refrigerator showing our new design;

FIG. 2 is a bottom, front and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a bottom, front and left side perspective view showing the refrigerator in an open state.

The broken lines in the drawings illustrate portions of the refrigerator which form no part of the claimed design. The oblique shade lines in the drawings indicate transparency.
